UNITED STATES PATENT OFFICE

2,587,966

EAR CLAMP

Joseph J. Cleary, Lexington, Mass.

Application October 30, 1950, Serial No. 192,955

3 Claims. (Cl. 128—346)

1

This invention relates to new and useful improvements in devices for use in the cutting of dogs' ears.

The primary object of this invention is to provide a device of this character which in its use will be as humane as possible, and which will enable those unskilled in the art to achieve professional results.

Another important object of this invention is to provide a device of this character which will permit the base of the ear to be cut as near to the head as possible.

Still another important object of this invention is to provide a device which may be efficaciously and accurately positioned on the dog's ear so as to obtain the precise cut desired.

Yet another important object of this invention is to provide a device of this character which will frictionally grip the ear of the dog in such a manner that the same will not be moved from its adjusted position by the dog shaking its head or the like, and which device will guide the cutting instrument in a single straight path, and which is adapted to be used with the conventional single edged safety razor blade.

A meritorious feature of the present invention resides in the fastening means employed to secure the opposite ends of the clamp plates together, and the registering elongated slots in the clamp plates which are disposed diagonally with respect to an imaginary straight line connecting the fastening means, so that the base of the ear may be cut as close to the head as possible.

Another feature of the present invention resides in the provision of registering elongated slots which will confine the movement of the cutting instrument, such as a single edged safety razor blade, to a single straight path of movement.

A final important feature to be specifically enumerated herein resides in the clamp plates being reduced in width intermediate their ends and the provision of openings in the clamp plates on opposite sides of the slots to materially reduce the weight of the device, such openings also serving the purpose of increasing the frictional engagement of the clamp plates with a dog's ear and cooperating with the lightness in weight of the clamp plates to prevent the device from being thrown from adjusted position when the dog shakes its head.

These, together with various ancillary objects and features of the invention which will become apparent as the following description proceeds,

2

are attained by the present invention, a preferred embodiment of which has been illustrated by way of example only in the accompanying drawings, wherein:

5 Figure 1 shows a pair of the devices forming the subject matter of this invention in use on the ears of a dog, and ready for the application of the cutting instrument;

10 Figure 2 is a transverse sectional view of the present invention taken upon the plane of the section line 2—2 of Figure 1; and

Figure 3 is a side elevational view of the present invention.

Reference is now made more specifically to the 15 accompanying drawings, wherein like numerals designate similar parts throughout the various views, and in which the device forming the subject matter of the present invention is designated generally at 10.

20 It will be understood that the device 10 is specifically adapted for the use of cutting the ears of certain breeds of dogs, such as boxers, Danes, Dobermans, etc. as is the customary practice. The device 10 is particularly well adapted for 25 this purpose, and comprises a pair of complementary clamp plates 12 and 14, each of which is elongated, and as clearly shown in Figure 1 have concaved side edges 16 so as to reduce the plates in width intermediate their ends and to thereby lessen their weight.

30 Means is provided for adjustably clamping the opposite ends of the plates 12 and 14 together, which includes threaded bolts or screws 18 extending through the plate 12 and having their heads 20 non-rotatably secured to the plate 12. The plate 14 is provided with suitable apertures 22 that slidably receive the screws 18 therethrough. A knurled thumb nut 24 is threaded on each of the screws 18 for urging the plates 35 12 and 14 together to clamp a dog's ear 26 therebetween.

It will be noted upon reference to Figure 1 that the fastening means formed of the screws 18, heads 20, and nuts 24 are disposed relatively at 45 the diagonal opposite ends of the plates 12 and 14. The plates 12 and 14 are provided with registering elongated slots 28 which extend substantially the entire length of the plates, and it is to be noted that the slots are diagonal with 50 respect to an imaginary line connecting the fastening means at the opposite ends of the plates, so that in use the lower ends of the slots will be disposed on the ear 26 closely adjacent the juncture of the ear 26 with the head of the dog 55 designated generally at 30. The slots 28 are

preferably on the order of two hundreds of an inch in width so as to slidably receive the edge of a safety razor blade therethrough, while not permitting the thickened edge of a single edged razor blade therethrough.

The plates 12 and 14 are provided with a plurality of registering openings 32 disposed on the opposite sides of the slots 28 which progressively increase in diameter towards the opposite extremities of the plates, such openings 32 being for the purpose of reducing the weight of the plates, and for also supplementing the frictional engagement of the plates 12 and 14 with the ear 26. It will be seen that the lightness of the plates afforded by the openings 32 and the cutting away of the opposite side edges of the plates coupled with the fact that the openings 32 increase the frictional engagement of the plates with the ear assures the retention of the device on the dog's ear even when the head is shaken.

The use of the present invention will be readily understood. With the nuts 24 loosened, the plates 12 and 14 are disposed on the opposite sides of the dog's ear 26, and the slots 28 disposed along the line of the intended cut, it being noted that the openings 32 also afford a means for visually assuring uniformity in the positioning of the devices on the dog's ears. The nuts 24 are then tightened, and a cutting instrument such as a razor blade, not shown, is inserted through the slots and swiftly drawn throughout the entire length of the latter. It is to be noted that the portion of the ear cut off is retained in its normal position until entirely severed, and is then only removed upon loosening the nuts 24 and removing the device from the animal's head. It will also be noted that a straight line cut is assured, so that a single swift stroke of the razor blade is sufficient to complete the operation with a minimum of pain to the animal.

It will be appreciated that the present invention, while being highly efficient and durable for the purposes intended, will be simple and inexpensive to manufacture and easy to use. While the same is preferably constructed of stainless steel, it will be readily seen that the same will lend itself to fabrication from many other materials.

From the foregoing, the construction and operation of the device will be readily understood and further explanation is believed to be unnecessary. However, since numerous modifications and changes will readily occur to those skilled in the art after a consideration of the 55

foregoing specification and accompanying drawings, it is not desired to limit the invention to the exact construction shown and described, but all suitable modifications and equivalents may be resorted to, falling within the scope of the appended claims.

Having described the invention, what is claimed as new is:

1. A device for use in the cutting of dog ears comprising a pair of elongated clamp plates adapted to receive the ear of a dog therebetween, adjustable fastening means securing the opposite ends of the plates together, said plates having registering elongated slots for the reception of a razor blade therethrough for guiding the same, one of said plates having a plurality of openings therethrough to one side of the slot to increase the frictional retention of the plate on the ear of a dog when the fastening means are tightened.

2. A device for use in the cutting of dog ears comprising a pair of elongated clamp plates adapted to receive the ear of a dog therebetween, adjustable fastening means securing the opposite ends of the plates together, said plates having registering elongated slots for the reception of a razor blade therethrough for guiding the same, said slots extending substantially the entire length of the plates and being disposed diagonal to and crossing an imaginary straight line connecting the fastening means.

3. A device for use in the cutting of dog ears comprising a pair of elongated clamp plates adapted to receive the ear of a dog therebetween, adjustable fastening means securing the opposite ends of the plates together, said plates having registering elongated slots for the reception of a razor blade therethrough for guiding the same, said slots extending substantially the entire length of the plates and being disposed diagonal to and crossing an imaginary straight line connecting the fastening means, one of said plates having a plurality of openings therethrough to one side of the slot to increase the frictional retention of the plate on the ear of a dog.
